UNITED STATES PATENT OFFICE

DANIEL W. WEAVER, OF GREENSBURG, INDIANA

CIRCUIT BREAKER

Application filed February 12, 1930. Serial No. 427,775.

The present invention relates to a circuit breaker particularly adapted for use on automobiles and has for its prime object to provide means for breaking the electric circuit of an automobile should the same turn over for the purpose of stopping the engine, putting out the light lit, and the like so as to eliminate danger of fires and other injuries or damages which might occur in such an accident.

Another very important object of the invention resides in the provision of a device of this nature which may be operated by hand if desired.

15 A still further object of the invention, is to provide, a hand operated device of this nature whereby the circuit may be broken while the car is parked in the garage thus reducing fire hazards.

20 Another very important object of the invention resides in the provision of a safety circuit breaker of this nature which is exceedingly simple in its construction, inexpensive to manufacture and install, thoroughly efficient and reliable in use and operation, compact and convenient in its arrangement of parts, easy to assemble and disassemble, and otherwise well adapted to the purpose for which it is designed.

25 With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the circuit breaker embodying the features of my invention,

40 Figure 2 is a vertical section therethrough taken substantially on the line 2—2 of Figure 1,

Figure 3 is a top plan view thereof,

45 Figure 4 is a top plan view of a battery showing the device attached thereto,

Figure 5 is a side elevation thereof,

Figure 6 is a perspective view of the funnel like member,

50 Figure 7 is a perspective view of one of the spring latches,

Figure 8 is a sectional view taken substantially on the line 8—8 of Figure 1,

Figure 9 is a sectional view taken substantially on the line 9—9 of Figure 2,

Figure 10 is an end elevation of the insulating block,

Figure 11 is a sectional view taken substantially on the line 11—11 of Figure 2,

Figure 12 is a side elevation of another embodiment of the invention showing the same in one position,

Figure 13 is a similar view showing the same in another position,

Figure 14 is a top plan view thereof, and

Figure 15 is a sectional view taken substantially on the line 15—15 of Figure 12.

Referring to the drawings in detail and first to Figures 1 to 11 inclusive it will be seen that the numeral 5 denotes a box having a removable cover 6 at the top thereof and adapted to be anchored in place by suitable fastening means 7. The bottom of the box is provided with a well 8 for housing a coil spring 9. A block of insulating material 10 is slidably mounted in the box and has transverse openings therethrough in which are located conducting rods 11. In opposite sides of the box are bushings 12 for receiving the ends of wires 13 which are adapted to be anchored in contact with the rods 11 by suitable means 14.

This contact relationship between the bars 11 and the wires 13 is had only when the block 10 rests on the bottom of the box as is shown in Figure 2, the spring 9 being adapted to normally raise the block 10 so as to break the contact. These wires 13 represent the wires which come from the terminals of battery B, the box 5 preferably being anchored on one end thereof.

This arrangement is shown merely by way of example and is not of the essence of the invention as will be readily appreciated that both of the lead wires of the battery or only one of them may be passed through this device.

A funnel like member 15 includes an oblong cone-shaped upper mouth or receptacle 16 which merges into an elongated depending tubular portion 17 the bottom end of

which is solid and externally threaded as is indicated at 18. Intermediate the ends of the tubular portion 17 there are oppositely disposed openings 19. This tubular portion 17 is slidable through an opening in the center of the cover 6 and the solid threaded end 18 is adapted to be threaded into a recess into the upper end of the block 10.

A body 20, which if desired may be rectangular but for the purpose of example is herein shown as cylindrical rests on top of the cover 6 circumjacent the intermediate portion of the tube 17 and is formed with diametrically opposite disposed radial openings 21 in which are slidable bullet shaped latch bolts 22 adapted to be extended through the openings 21 by means of springs 23 which impinge against the latch bolts and also against a ring 24 circumjacent the body 20 and anchored to the cover 6 by means of reusable spring clips 25.

A bar 26 is slidable in the tube 17 and intermediate its ends is formed with an upwardly tapered wedge portion 27 merging in 25 to a reduced extension 28 having a head 29 located within the receptacle 16. A spring 30 is in the bottom of the tube 17 and impinges upwardly against the bar 26 sufficiently to urge the wedge shaped intermediate portion 30 27 upwardly for forcing the latch bolts 22 outwardly and then the spring 9 is strong enough to push the block 10 upwardly with the funnel shaped member 15 forcing the bolts 22 out of the openings 19 thereby breaking the 35 circuit as will be apparent.

To normally prevent the operation just described a ball 31 is mounted in the receptacle 16 and therefore rests on the head 29 and this ball is of sufficient weight to overcome the 40 tension of the spring 30. It will be seen, however, that should the vehicle turn over the ball 31 will be thrown out of the receptacle and therefore the spring 30 would come into action to allow the operation just described for 45 breaking the circuit.

It may be desirable, at times, to break this circuit and therefore I provide a hand operating mechanism which includes the fork 32 having its ends anchored to the ring 20 and 50 any suitable means 33 may be provided for pulling this fork 32 so as to raise the body 20 and the ring 24, sufficient pressure being used to overcome the spring clip 25 thereby leaving the spring 9 free to raise the block and 55 break the circuit.

In Figures 12 to 15 inclusive I have shown another embodiment of the invention wherein numeral 40 denotes a casing one end of which is open and has a cap plate 41 thereon 60 anchored in place by suitable fastening means 42.

A block of insulating material 43 is rockable in the casing 40 and has extending diametrically thereacross one or more conductor bars 44 with which contacts or wires 45

are engaged. A shaft 46 extends from one end of the block 43 and is journaled through the center of the cap plate 41 and has a reduced terminal extension 47 which in turn has a reduced extension 48.

A spring 49 coiled about the shaft and having one end anchored in the cap 41 and has one end anchored in the block 43 and is normally tensioned to rock the block 43 so as to disengage the conduit bars 44 from the 75 wires 45 and break the circuit. However, on the end 47 there is an arm 50 from the terminal of which extends oblong funnel shaped receptacle 51 in which is disposed a ball 52 of sufficient weight to overcome the tension 80 of the spring 49.

It is preferable to use a spring clip 53 to engage the arm 50 and aid in holding the same in the position shown in Figure 12.

If the vehicle should upset, the ball would be thrown from the receptacle 51 thereby freeing the arm 50 and allowing the rocking of the block 43 to circuit breaking position. The arm 50 is limited in its movement by a stop 55. To operate the device by hand I 90 mount a bell crank lever 56 on the extension 48 and provide a pin 57 on the arm 50 with which one arm of the bell crank will contact when rocked by a cable 58 or the like so as to break the circuit as will be apparent.

It is thought that the construction, operation, utility and advantages of this invention will now be quite apparent to those skilled without a more detailed description thereof.

The present embodiments of the invention have been disclosed in considerable detail merely for the purposes of exemplification since in actual practice they attain the features of advantage enumerated as desirable 100 in the statement of the invention and the 105 above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A device of the class described comprising a casing, a movable block in the casing, a conductor bar in the block, means for anchoring wires to the casing to engage the ends of the bar when the block is in one position, spring means normally urging the block from said one position to break the circuit between the wires, a tube slidable through one end of the casing and anchored in the block, latch means for holding said tube with the spring under tension and the circuit closed, and means for releasing said latch means.

2. A device of the class described comprising a casing, a movable block in the casing, a conductor bar in the block, means for anchoring wires to the casing to engage the 120 125 130

- ends of the bar when the block is in one position, spring means normally urging the block from said one position to break the circuit between the wires, a tube slidable 5 through one end of the casing and anchored in the block, latch means for holding said tube with the spring under tension and the circuit closed, a member slidable through the tube being tapered upwardly and intermediately 10 ate its ends to form a wedge portion for releasing the latch means, spring means under the member urging the same upwardly, a receptacle at the top of the tube, a weight element in the receptacle to engage the member and overcome the tension of the spring thereunder. 15
3. A device of the class described comprising a casing, a movable block in the casing, a conductor bar in the block, means for anchoring wires to the casing to engage the ends 20 of the bar when the block is in one position, spring means normally urging the block from said one position to break the circuit between the wires, a shaft rockable through one end of the casing and anchored in the block, an arm on the shaft exteriorly of the casing, a spring clip on the casing engageable with said arm for holding the latter against the action of the spring for normally 25 retaining said block in said one position, a receptacle on said arm, and a weight element in said receptacle for overcoming the tension on said spring so that when said weight element is out of said receptacle said spring 30 moves the block to break the circuit. 25
4. A device of the class described comprising a casing, a movable block in the casing, a conductor bar in the block, means for anchoring wires to the casing to engage the ends 35 of the bar when the block is in one position, spring means normally urging the block from said one position to break the circuit between the wires, a shaft rockable through one end of the casing and anchored in the block, an arm on the shaft exteriorly of the casing, a spring clip on the casing engageable with said arm for holding the latter against the action of the spring for normally 40 retaining said block in said one position, a receptacle on said arm, and a weight element in said receptacle for overcoming the tension on said spring so that when said weight element is out of said receptacle said spring 45 moves the block to break the circuit, a stop pin extending from said casing engageable with said arm for limiting the movement of said arm when the latter is actuated by said spring, a bell crank on said shaft and said arm having a pin engageable with one arm 50 of the bell crank whereby upon actuation of said bell crank said arm will be moved into engagement with said spring clip. 55
5. A device of the class described comprising a casing, a movable block in the casing, a conductor bar in the block, means for anchoring 60 wires to the casing to engage the ends of the bar when the block is in one position, spring means normally urging the block from said one position to break the circuit between the wires, a member fixedly engaged with the block and movable therewith, said member extending through one end of the casing, yieldable means for holding said member with the spring under tension and the circuit closed, and means for 65 releasing said yieldable means. 70
6. In a device of the class described, a movable member, spring means normally urging said movable member in one direction, a second member carried by the first mentioned member and movable therewith, means acting on said second member oppositely to the action of said spring means on said first mentioned member, said last mentioned means including a conical container, and a weight 75 normally arranged in the container. 80
7. In combination, a pair of circuit wires having adjacent ends disposed in relatively spaced fixed relation, a movable member, a conductor rod carried by said movable member, oppositely acting means acting on said movable member for normally retaining the same in one position with the conductor rod engaging the same ends of said circuit wires for normally retaining the circuit closed, said 85 oppositely acting means including a member normally urging said movable member in one direction to break the circuit, and a second member displaceable in response to shock whereby said movable member is free to 90 move for moving said conductor rod out of engagement with the ends of the circuit wires, and manual means for displacing said displaceable member independently of shock. 95
8. A device of the class described comprising in combination a pair of circuit wires having adjacent ends arranged in relatively spaced fixed relation, a block arranged between said ends and movable relative thereto, a conductor rod carried by said block, means 100 normally urging said block in one direction for moving said conductor rod out of engagement with the said ends of said circuit wires, means acting against the last mentioned means for normally retaining said block in 105 one position with the conductor bar engaging said ends of said circuit wires, and including an element displaceable in response to shock for freeing said blocks, whereby the latter may be moved under action of the first mentioned means, and manual means for effecting a displacement of said element independently of shock, said manual means including a container, adapted to receive therein said displaceable element, means operatively connecting said container with said block, and means for moving said container relative to 110 said block. 115
- In testimony whereof I affix my signature. 120
- DANIEL W. WEAVER. 125
